UNITED STATES PATENT OFFICE.

WILLARD E. DOW, OF BRAINTREE, MASSACHUSETTS.

ELECTRICAL IGNITION APPARATUS FOR GAS-ENGINES.

SPECIFICATION forming part of Letters Patent No. 728,882, dated May 26, 1903.

Application filed August 2, 1902. Serial No. 118,033. (No model.)

To all whom it may concern:

Be it known that I, WILLARD E. Dow, a citizen of the United States, and a resident of Braintree, county of Norfolk, State of Massachusetts, have invented an Improvement in Electrical Ignition Apparatus for Gas-Engines, of which the following description, in connection with the accompanying drawing, is a specification, like letters on the drawing 10 representing like parts.

As commonly constructed gas-engines are provided with a current-interrupter for the spark-plug on or connected with the shaft of the engine and a usual high-voltage apparatus comprising an induction-coil, battery, condenser, and vibrator.

One of the difficulties experienced in connection with the above construction, especially when used for automobiles, is that 20 when the speed becomes exceedingly rapid the vibrator is apt to cease to work or "stick," thereby short-circuiting the sparking current; and accordingly it is the purpose of my present invention to provide a construction 25 which will prevent any ill effects from excessive speed of the engine.

The various details of my invention will appear more fully from the following description, reference being had to the accompanying drawing, in which I have illustrated diagrammatically one embodiment of my invention.

In the drawing the figure shows my invention in diagram.

Let A indicate a battery or any other source of electric energy, from which the wire a leads to one end of the primary p of a proper induction-coil I, whose secondary s leads to the spark-plug P of the engine-cylinder d, the 35 opposite end of the primary being connected by a wire a' to a condenser C, which connects by a wire a² from its opposite end with the battery A. In the old and usual construction the mechanical interrupter operated by 40 the engine would be interposed in the wire a² and a vibrator would be connected around the condenser between said interrupter and condenser to the wire a', so that under normal conditions of operation the vibrator 45 would serve to discharge the condenser in the usual manner and the engine would work properly; but in case the vibrator should

stick or cease to work it is obvious that it would produce a short circuit around the condenser, thereby cutting out the latter entirely and rendering the apparatus inoperative. Instead of this construction I provide a vibrator or automatic electrical interrupter B in a shunt-circuit a³ a⁴, which includes the mechanical interrupter e, operated by 50 any suitable mechanism, as a cam E, and connected thence by a wire a⁵ to the battery or wire a². Preferably, also, I provide a shunt-circuit a⁶ around the vibrator B, so that upon turning the switch a⁷ thereof the 55 interrupter may be cut in or out, as desired, according to the special conditions of the moment. When the engine is first started, and therefore turns slowly, the vibrator B is necessary in order to produce the proper conditions for operating the sparking or igniting 60 apparatus for the explosion-chamber of the engine; but when the engine gets well started and increases its speed it becomes unimportant in my invention whether the vibrator 65 works properly or not, (and, in fact, it is often desirable to short-circuit it by means of the switch a⁷,) because there can be no short circuit of the condenser, as was formerly the 70 case, inasmuch as the interrupter e is in the shunt-circuit a³ to a⁵ and there is no possibility of a short circuit between it and the condenser around the latter. The result is that 75 the condenser-discharge is always effective every time a spark is required for the explosion-chamber of the engine, and the condenser 80 will be discharged either by the vibrator B or by the interrupter e of the engine, the former being relied upon for starting the engine and the latter after the engine has gained high 85 speed. In no case can the condenser be short-circuited. This is of very great importance 90 in automobile work; but I do not intend to limit my invention to this one application thereof, as it is obvious that it may be used 95 to advantage in other situations. It will also be understood that while I have described and shown my invention diagrammatically, the parts being separated for convenience of 100 illustration, in practice they are mounted together in small compass.

Having fully described my invention, what I claim as new, and desire to secure by Letters Patent, is—

1. In an apparatus for operating a gas-engine, a source of energy, an induction-coil, a sparking device operated thereby for driving the engine, a condenser, a mechanical interrupter, and a vibrator, said interrupter and vibrator being in series with each other in a shunt-circuit around said condenser.
2. In an apparatus for operating a gas-engine, a source of energy, an induction-coil, a ¹⁰ sparking device operated thereby for driving the engine, a condenser, a mechanical interrupter, and a vibrator, said interrupter and

vibrator being in series with each other in a shunt-circuit around said condenser, and a short circuit and switch therefor around said ¹⁵ vibrator.

In testimony whereof I have signed my name to this specification in the presence of two subscribing witnesses.

WILLARD E. DOW.
